CLAIM

The ornamental design for the robotic mower, as shown and described.

DESCRIPTION

FIG. 1 is a perspective view of a robotic mower in accordance with an embodiment of the present invention; FIG. 2 is a front view of the robotic mower of FIG. 1; FIG. 3 is a rear view of the robotic mower of FIG. 1; FIG. 4 is a right side view of the robotic mower of FIG. 1; FIG. 5 is a left side view of the robotic mower of FIG. 1; FIG. 6 is a top view of the robotic mower of FIG. 1; and, FIG. 7 is a bottom view of the robotic mower of FIG. 1. The broken lines of the robotic mower in FIGS. 1-7 form no part of the claimed design.

1 Claim, 7 Drawing Sheets
